UNITED STATES PATENT OFFICE

ELMER KEEBLER, OF CHICAGO, ILLINOIS, ASSIGNOR TO MECHANICAL MANUFACTURING COMPANY, OF CHICAGO, ILLINOIS, A CORPORATION OF ILLINOIS

BUMPING POST

Application filed October 8, 1929. Serial No. 398,241.

My invention relates to bumping posts of the type that are used in connection with railway cars and the like.

In the operation of bumping posts of the class generally employed today, it is very often found that when a considerable impact is imparted to the post the strain is transmitted through the parts into the track with such force that in many instances both the track structure and the bumping post itself suffer considerable damage. By my novel construction hereinafter described, the outstanding objections to the present type of post are overcome and a novel and effective type of bumping post is provided. The present application is in some aspects an improvement on the construction described and claimed in Letters Patent No. 1,348,223, issued to me on August 3, 1920.

It is an object of the present invention to provide a simple practical and efficient type of bumping post.

Another object is to provide a bumping post in which standard rail lengths may be employed as component parts of the structure.

Another object is to provide a bumping post in which straight rail sections may be employed, as contrasted with the deformed sections which have heretofore been employed.

A further object is to provide a bumping post in which the likelihood of breakage of the rails is reduced to a minimum.

Further objects and advantages will become more apparent from a reading of the following specification in the light of the accompanying drawings in which—

Figure 1 is a plan view of a bumping post constructed in accordance with the present invention;

Figure 2 is a view in side elevation of the structure disclosed in Figure 1;

Figure 3 is a fragmentary enlarged view taken along the line 3, 3 of Figure 2; and

Figure 4 is a fragmentary enlarged view in section taken along the line 4, 4 of Figure 2.

Turning to the drawings, the reference numeral 10 indicates a bumping block which

is adapted to receive blows from railway cars and the like, and as illustrated, the post is supported at its forward side by means of downwardly diverging tension members 12, and is braced in the rear by means of downwardly diverging compression members 11. In operation, blows and jars imparted to the pumping block 10 are transmitted to the members 11 and 12 to the track and road bed.

As illustrated in the drawings, the tension members 12, which extend downwardly from the forward side of the bumping block comprise short lengths of standard rail, whereas the compression members which extend downwardly in the rear of the bumping block are formed of channel irons. It is to be understood, however, that structural members of different kinds may be substituted for those specifically illustrated in the drawings without departing from the scope of the present invention. Thus, standard rail lengths might be employed in the rear for the compression members as well as in front for the tension members, or, on the other hand, channel irons, or flat beams, could be substituted for the illustrated standard rail lengths.

The compression members 11 are suitably secured to the bumping block by means of bolts 13 and the lower extremities of the members are fastened to the track rails (herein indicated by the reference numeral 14) by means of a tie rod 15 which spans the space between the track rails, thence extends through apertures formed in the lower extremities of the compression members 11, and finally project through openings formed in the web portions of the track rails 14. In order to hold the assembled parts against movement relatively one to the other, each end of the tie rod 15 is provided with screw-threads adapted to cooperate with an inner lock-nut 19 and an outer lock-nut 19'. Interposed between the lock-nuts and the track rails and compression members are wedge blocks 16, 17 and 18 which insure a thorough gripping action between the assembled parts.

It will be observed from an inspection of Figure 4 that the lower edge of the compres-

sion member 11 is cut on a bias as indicated by the reference numeral 20 in order that it may rest firmly upon the base flange of the running rail 14.

5 Turning now to the manner in which the tension members 12 are connected, the reference numeral 21 indicates a plurality of bolts which secure the upper extremities of the members to the bumping block 10. For an 10 understanding of the manner in which the lower extremities of the tension members are secured to the running rails 14 of the track attention is respectfully invited to a consideration of Figure 3 in conjunction with 15 Figures 1 and 2. As therein illustrated, a clamping plate 24 extends lengthwise for a short distance of the running rail 14 and is firmly secured thereto by means of bolts 26 which extend through apertures in the running rail 14 and are seated upon an anchor plate 27 located on the outer side of the rail 14. The anchor plate is of approximately the same length as the clamping plate 24 and together the two parts cooperate in forming an 20 extremely rigid and durable connection. Extending inwardly from the clamping plate 24 is an integrally formed connecting arm 23 which is so shaped relatively to the clamping plate 24 as to extend upwardly in the same 25 direction as the tension member 12. The connecting arm 23 is suitably and rigidly secured to the tension member 12 by means of fastenings 25 shown in the form of bolts and nuts.

From so much of the description as heretofore given it will be appreciated that the bumping block 10 is securely mounted upon the tension and compression members which in turn are rigidly connected to the running rails 14. In spite of the rigidity of the construction so far described, it has been found that when a severe blow is imparted to the block 10, there is a tendency on the part of the lower extremities of the tension member 12 to move suddenly inward toward one 40 another thereby exerting a buckle action upon the running rails which tends to displace them from their proper positions. In order efficiently to overcome this tendency the present invention contemplates the provision of 45 means for adequately resisting such strains and as illustrated herein the said means comprises a bracing rod 29 which extends beneath the base flanges of the running rails and passes through apertures formed in the downwardly projecting extremities of the tension members 12 (Figure 3). In order to hold the bracing rod 29 in close contact or engagement with the base flange of the running rail, as shown in Figure 3, there is provided a 50 drawing member 30 having an upper inwardly extending cam-like portion which overlies the outer edge of the base flange of the running rail. Nuts 31 are provided for holding the drawing member in place and it 55 will be appreciated from an inspection of

Figure 3 that in applying the nuts and drawing member, the latter during the course of its application presses, or draws, the bracing bar 29 firmly and tightly into engagement with the base flange of the running rail 14. 70 Not only does the drawing member 30 serve to draw the bracing bar into proper position during assemblage of the device, but it also serves to hold the bar in proper position during use. The bracing bar alone will not, of course, resist any tendency of the rails 14 to buckle, or collapse, inwardly when a tremendous blow is imparted to the bumping block 10, but the invention contemplates the employment of means for resisting this tendency and as illustrated such means takes the form of a spacer pipe 32 which closely surrounds the bracing bar 29 and extends between the opposite inner web faces of the tension members 12. Thus, in use any tendency on the part of the lower extremities of the tension members to move toward one another is adequately resisted and overcome by means of the spacer 32. It must be recognized, however, that devious kinds of spacing members and means may be employed and that the invention is in no wise limited to the exact form illustrated in the drawings.

Having thus described my invention, what I claim as new and desire to procure by 95 United States Letters Patent, is:

1. A bumping post, comprising in combination a bumping block, compression members secured to said bumping block and to track rails, and tension members comprising a pair of bars straight throughout their entire length attached to said bumping block and extending downwardly and outwardly between the track rails, and means for attaching said bars to the track rails.

2. A bumping post, comprising in combination a bumping block, compression members secured to said bumping block and to track rails, and tension members comprising a pair of bars straight throughout their entire length attached to said bumping block and extending downwardly and outwardly between the track rails, and means for attaching said bars to the webs of the track rails.

3. A bumping post, comprising in combination a bumping block, compression members secured to said bumping block and to track rails, and tension members comprising a pair of bars straight throughout their entire length attached to said bumping block and extending downwardly and outwardly between the track rails, and terminating below the track rails, and means for attaching said bars to the track rails.

4. A bumping post, comprising in combination a bumping block, compression members secured to said bumping block and to track rails, and tension members comprising a pair of bars straight throughout their en-

- tire length attached to said bumping block and extending downwardly and outwardly between the track rails and terminating below the track rails, and means for attaching
- 5 said bars to the webs of the track rails and a member extending through the lower ends of said bars and beneath the rails having means for clamping the opposite ends thereof to the flanges of the track rails.
- 10 5. A bumping post, comprising in combination a bumping block, compression members secured to said bumping block and to track rails, and tension members comprising a pair of bars straight throughout their entire length attached to said bumping block and extending downwardly and outwardly between the track rails and terminating below the track rails, and means for attaching
- 15 said bars to the webs of the track rails and a member extending through the lower ends of said bars and beneath the rails having means for clamping the opposite ends thereof to the flanges of the track rails, said last named member also having means mounted
- 20 25 thereon having abutting and spacing engagement with the lower ends of said pair of bars.
6. A bumping post comprising in combination a bumping block, compression members secured to said bumping block and to track rails, and tension members comprising a pair of bars straight throughout their entire length attached to said bumping block and extending downwardly and outwardly
- 30 35 between the track rails, and means for attaching said bars to the track rails and a compression member extending between the lower ends of said pair of bars having abutting and spacing engagement therewith.
- 40 7. A bumping post comprising in combination a bumping block, compression members secured to said bumping block and to track rails, and tension members comprising a pair of bars straight throughout their entire length attached to said bumping block and extending downwardly and outwardly between the track rails to a point below said track rails, and means for attaching said bars to the track rails and a compression member
- 45 50 disposed in a plane below the track rails and extending between the lower ends of said pair of bars with abutting and spacing engagement therewith.

Signed at Chicago, Illinois, this 1st day of
55 October, 1929.

ELMER KEEBLER.
